ELECTRIC KEY PUNCH

Filed June 1, 1925

UNITED STATES PATENT OFFICE

CLAIR D. LAKE, OF BINGHAMTON, NEW YORK, ASSIGNOR TO THE TABULATING MACHINE COMPANY, OF ENDICOTT, NEW YORK, A CORPORATION OF NEW JERSEY

ELECTRIC KEY PUNCH

Application filed June 1, 1925. Serial No. 34,080.

This invention relates to perforating machines and more particularly to means for effecting adjustments in electric key punch machines.

5 Upon depression of any one of the selecting keys of such a machine of an approved type an interposer is advanced to an effective position between a selected punch and an operating member. As such interposer approaches 10 its effective position the circuit of the punch magnet is closed to actuate said operating member which through the operatively positioned interposer operates the selected punch. Upon completion of each punching operation 15 the circuit of the punch magnet is again broken. In the usual operation of such machines the armature of the punch magnet strikes the core of such magnet in each punching operation and the noise resulting from such strokes 20 in rapid succession is extremely undesirable. Such strokes also may disturb the adjustments of different parts of the machines. In order to avoid such undesirable conditions it is necessary to prevent the armature from 25 striking the core of the magnet. It is also desirable to so adjust the related parts that the best results can be obtained.

One of the objects of the invention is to 30 provide efficient and economical means for attaining the desired results.

Other objects of the present invention reside in improvements in the arrangement of the punch magnet circuit to the general end that sparking at contacts is obviated and the 35 action of the punching magnet is speeded up.

Other objects of the invention are to provide means for limiting the operative movement of the armature of the punch magnet to restrain it from striking the core of the magnet, means for adjusting the magnet so that the armature thereof will approach it squarely; means for adjusting the magnet toward and from the armature in its normal or retracted position; adjustable means for determining the clearance between the upper surfaces of the interposers and the punch-operating device or depresser; adjustable means for determining the relation between the armature of the punch magnet and the punch-operating device or depresser; and adjust-

able means for breaking the circuit of the punch magnet when the armature thereof reaches a predetermined position.

These and other objects of the invention may be attained as follows: The armature 55 may be pivoted and the magnet may be adjusted forwardly and rearwardly so that the adjacent face of the magnet will be in the proper position relative to the adjacent end of the magnet core when the armature is 60 drawn toward the magnet. The magnet may have two core ends facing the armature and arranged longitudinally of the axis about which the armature swings and the magnet may be so adjusted that the plane determined 65 by the two ends of the magnet core will be parallel to said axis of the armature. Provision may be made of a cushioning buffer for engagement by the armature when retracted and adjustable to assist in determining the clearance between the interposers and the depresser or operating member therefor. An adjustment may also be interposed in the 70 train of connections between the armature and the depresser for the interposers for use 75 to assist in determining the limiting positions of the depresser and the clearance between the depresser in its normal position and the interposers. Another feature resides in the provision of suitable means such as a 80 toggle-like linkage or toggle for preventing the armature from striking the core. The toggle is at the opposite side of the armature from the magnet, and is pulled substantially straight when the armature reaches the limit 85 of its movement toward the magnet. The end of the toggle away from the armature is adjustably connected and serves various purposes, for example, that of determining the proper final position of the armature when 90 the magnet is energized.

It should be understood that the adjustable buffer, the adjustable toggle structure, the adjustment interposed in the train of connections between the armature and the depresser, and the adjustment for the magnet, although each has its own function, all 95 cooperate in producing an effective machine for the purposes specified.

In connection with the toggle provision is 100

made of a spring device which is tensioned just as the toggle reaches its straight condition and which, when the magnet is deenergized, acts on the toggle just long enough to 5 start the breaking thereof.

To break the punch magnet circuit as soon as a selected punch has been actuated, provision is made of two horizontally arranged spring contacts and depending link lifted each 10 time an interposer is moved into effective position and having a shoulder to engage the lower spring contact and raise it into contact with the upper spring contact, the link extending downwardly adjacent the horizontal 15 armature-actuating link. Adjustably mounted on the horizontal link is a lug to engage such depending link when the armature reaches the end of its effective stroke and release the lower spring contact to break the 20 punch magnet circuit.

Other features and objects will hereinafter appear.

Fig. 1 is a sectional side elevation of a preferred embodiment of the invention;

25 Fig. 2 is a view in section taken along the line 2—2 of Fig. 1; and

Fig. 3 is a detail view showing the armature of the punch magnet in the position assumed upon energization of the magnet.

30 Fig. 4 is a circuit diagram.

Fig. 5 is a top sectional view of the key-operated hook showing its position relative to the lower contact blade in the punch-operating circuit.

35 Upon depression of any one of a set of punch selecting keys 1 a corresponding bell crank 2 is rocked against the action of the spring 3 and a corresponding interposer 4 is advanced so that the upper edge thereof lies 40 under a transverse member or depresser 5. There is an interposer for each selecting key 1 and each of such interposers overlies the head of a corresponding punch 6, the upper edge of the interposer being cut away at 7

45 so that when the interposer is in its normal retracted position a downward movement of the depresser 5 will not actuate the interposer. When, however, any one of the interposers is advanced to effective position a downward

50 movement of the depresser 5 will depress the effectively positioned interposer and consequently the corresponding punch 6 against the action of its spring 8 to punch or perforate a card lying between guide member 9

55 and a die 10. Normally the depresser 5 is held in raised position by means of a spring 11 interposed between a fixed part of the frame and a lug 12 projecting from the bail 13 pivoted at 14 and of which depresser 5 is 60 a part.

Each of the interposers 4 is notched at its lower side to form a shoulder 15 for engagement by a cross bar 16 of a bail 17 pivoted at 18 on a fixed part of the frame 19. The bail 65 17 is provided with a rearwardly extending

arm 20 to which is pivoted at 21 a depending link 22 urged to the left, as seen in Fig. 1 by a spring 23 attached at its other end to a fixed part of the frame. Near the lower end of the link 22 it is provided with a shoulder 24 forming a hook to engage an insulating member 25 on a leaf spring 26 with a contact point 27 thereon. Upon advance movement of any one of the interposers 4 the bail 17 will be swung about its pivotal axis and the link 22 lifted to bring the contact point 27 into engagement with a contact point 28. This results in closing the circuit of a punch magnet 29 thus energizing the magnet and swinging an armature 30 in a counter clockwise direction about its pivot 31. The armature in this movement acts through a link 32 and an arm 33 to rock the shaft 34. Extending to and fixed upon this shaft is an arm 35 pivotally connected at its forward end with a bent link 36 pivoted at its upper end at 37 to one arm of the bail 13. Rocking of the shaft 34 by the armature in its movement towards the magnet will therefore result in swinging the depresser 5 downwardly to engage the effectively positioned interposer and the corresponding punch 6.

It is desirable to deenergize the magnet as soon as the punch has been operated in this manner and restore the parts to the normal position. To this end the link 22 is extended downwardly below the shoulder 24 and such extended portion normally rests against a lug 38 extending across the link 32 from an angle lever or member 39 pivoted at 40 on the link 32 and having in the portion extending away from the pivot a slot 41 concentric with the pivot 40 and through which passes a set screw 42 threaded into the link 32. When the armature 30 approaches the core of the magnet the lug 38 swings the link 22 to the right, Fig. 1, and disengages the shoulder 24 from the insulating member 25. It will be apparent that the disengagement of the shoulder 24 from the insulating member 25 may be adjusted with precision by releasing the set screw 42 and turning the member 39 to the desired extent about its pivot 40.

When the armature 30 is in its normal or retracted position the rear of the armature or armature frame engages a member 43 of suitable material to cushion the shock of engagement and prevent any unnecessary noise. Such member 43 is mounted in an enlarged end of a member 44 having a threaded rear end extending through a web 45 of the frame and adjustably held in position by means of nuts 46. As will be brought out more clearly hereinafter the adjustment in position of the member 44 has a bearing upon the clearance between the depresser 5 and the upper edges of the interposers 4. Such clearance of the depresser 5 above the interposers 4 and the throw of the depresser 5 may also be regulated to some extent by an adjustable con-

nection between arm 33 and the link 32 as disclosed herein. As shown herein provision is made of an adjustable eccentric pivotal connection 47 comprising a screw having its stem threaded into link 32 and a portion 47' intermediate the threaded stem and the head of the screw. The portion 47' is eccentric to the threaded stem and passes freely through arm 33. By rotating the screw, the eccentric portion 47' varies the relative angular positions of arm 33 and link 32. Arm 33 being rigidly movable with arm 35, the clearance of the depresser 5 above the interposers may in this manner be accurately regulated.

15 The striking of the armatures against the cores 48 of such magnets 29 in machines of this kind causes the machines to be very noisy and also tends to cause excessive vibration and loss of adjustment. To the end of obviating these disadvantages provision is made of a toggle like linkage generally designated 49 in Fig. 2 connecting the armature 30 to the web 45 and limiting the armature in its movement toward the cores 48 of the magnet. This 20 linkage comprises a link 50 pivoted to the armature at the lower edge thereof and connected at the other end by means of a bolt 52 to spaced links 53 pivoted by means of a bolt 54 to a member or block 55 provided 25 with a rearwardly extending threaded shank 56 passing through web 45 and adjustably secured thereto by nuts 57. The block 55 is also provided with a tongue 58 projecting between the links 53 and overlying the cross 30 bar 59 of a bail 60 having arms 61 loosely mounted on the bolt 54 and engaging the outer faces of the links 53. Projecting upwardly from the cross bar 59 and between links 53 is a lug 62 to which is attached the 35 lower end of a spring 63 connected at its upper end with a fixed pin 64. It will be seen from inspection of Fig. 3 that upon deenergization of the magnet 29 the spring 63 will swing the bail 60 until the cross bar 40 45 comes into engagement with the tongue 58. This movement although very slight will be sufficient to break the toggle linkage 49 and enable the armature 30 to be swung to its retracted or normal position as shown 50 in Fig. 1.

The magnet 29 comprises two cores 48 joined at the rear by the yoke 65 and coils surrounding each of said cores 48. Provision is made for adjusting the magnet for purposes to be brought out more clearly herein-after. For such adjustment use is made of bushings 66 threaded into a web 67 of the frame 19 and engaging at their inner ends the yoke 65. Such bushings are connected 55 with the yoke 65 by means of set screws 68 passing through the bushings and threaded into the yoke and after adjustment of the bushings by means of the heads 69 thereof they may be locked in position in the web 60 65 67 by means of lock nuts 70.

The adjustable bushings 66 and set screws 68 may be used to shift the magnet 29 bodily to the left or right (Fig. 2) or by varying the adjustments of the two bushings may shift the yoke so as to incline the magnet to either one side or the other. By the second of these adjustments the ends of the cores 48 may be brought into such positions that they will be equally distant from the armature 30 and by the first of these adjustments the ends of the cores 48 may be positioned so as to be separated to a slight extent from the adjacent face of the armature when such face is substantially vertical. (Fig. 3.)

To prevent the armature 30 from passing beyond the position shown in Fig. 3 the nuts 57 are so positioned on the shank 56 that the toggle 49 will be completely straightened when the armature reaches such position.

Then the eccentric pivotal connection 47 may be adjusted to determine the lower limit of the stroke of the depresser 5 and therefore of the punches 6, and the nuts 46 may be adjusted on the member 44 to position the member 43 so that when the armature 30 is in engagement therewith the depresser 5 will have the desired clearance above the interposers when in its normal position.

It should be understood that the manner of making the desired adjustments may be varied and that various changes in the construction and arrangement of parts may be made without departing from the spirit of the invention.

Referring to the circuit diagram (Fig. 4), a condenser 70' is shown in a circuit 71 which includes a resistance 72. This condenser minimizes the sparking at contacts 27-28 and also speeds up the operation of the machine as a whole. This speeding up of the machine operation is secured by rapidly killing the induction in the magnet 29. Without the condenser the magnet 29 would remain energized to a certain extent at least during the period in which the spark occurred at the contacts. The purpose of resistance 72 is to prevent high and excessive oscillatory current discharges from the condenser 71.

What I claim is:

1. A punching machine of the type having light punches for perforating record cards or the like and punch-operating means including a punch-actuating device connected to the armature of an operating solenoid; characterized by the fact that retarding means are provided for the punch actuating device, comprising a stationary member and a toggle linkage connected at one end to said member and at the other end to said armature.

2. A machine as set forth in claim 1, further characterized by the fact that means are provided to normally hold the toggle linkage broken when the armature is released from the attraction of the solenoid.

3. A punching machine of the type having

- light punches for perforating record cards or the like operated by a reciprocatable punch-actuating device connected to the armature of an operating solenoid; characterized by the fact that means are provided for determining the end of the punch-actuating stroke of the device, comprising a stationary member located at the side of the armature opposite the solenoid and a connection located between the said member and armature for positively arresting the movement of the armature toward the solenoid at a definite point and simultaneously arresting the punch-actuating movement of said device.
4. A machine such as described in claim 3, and means for adjusting the connection between the armature and stationary member for adjusting the point at which the punch-actuating stroke of said device terminates.
5. A machine such as described in claim 3, said connection between the member and armature consisting of rigid links pivoted to each other.
6. In a record punching machine of the type wherein light punches for perforating record cards or the like are operated by a magnet, an armature therefor and punch-operating means actuatable by the armature, means at the other side of the armature from the magnet coating with said armature for limiting the movement of the punch-operating means comprising a toggle linkage pivotally connected at one end with the armature and at the other end with a fixed part of the machine, means tending to break the toggle linkage, and means for rendering the last-mentioned means ineffective as soon as the breaking action is started.
7. In a record punching machine of the type wherein light punches for perforating record cards or the like are operated by a magnet, an armature therefor, and punch-operating means actuatable by the armature, means for limiting the movement of the punch-operating means comprising a toggle linkage connecting the armature with a fixed part of the frame, and a spring device tensioned by the toggle linkage as the latter is straightened by the armature and effective to produce a slight breaking of the toggle linkage to permit further breaking of the toggle by the armature as it returns to its normal position.
8. In a record punching machine of the type wherein light punches for perforating record cards or the like are operated by a magnet, an armature therefor and punch-operating means actuatable by the armature, means for limiting the movement of the punch-operating means comprising a toggle linkage arranged to be straightened by such movement of the armature, a spring-tensioned lever in the path of said linkage, and a stop to determine the position of said lever for actuation by said linkage as the latter becomes fully extended and to restrain said lever as soon as it starts the breaking of said linkage.
9. In a record punching machine of the type wherein light punches for perforating record cards or the like are operated by a magnet, an armature therefor and punch-operating means actuatable by the armature, means for limiting the movement of the punch-operating means comprising a toggle linkage arranged to be straightened by such movement of the armature, a member on which the link of said linkage farthest from said armature is pivoted, a tongue projecting from said member toward the armature, a spring-urged lever pivoted on said member and extending beneath said linkage for engagement thereby and beneath said tongue so that said lever will be displaced from said tongue by the linkage when straightened by the magnet and will be checked by said tongue after starting the breaking of said linkage when the magnet is deenergized.
10. In a record punching machine having a set of punches, a depresser overlying said punches and interposers movable one by one into effective position between the depresser and the punches, a magnet, an armature for said magnet, means for adjustably determining the normal position of said armature when withdrawn from said magnet, and a connection between the armature and the depresser for actuating the latter and adjustable for independently of the aforesaid means determining the clearance between the depresser and the interposers when the armature is in said normal position.
11. In a record punching machine having a set of punches, a depresser overlying said punches and interposers reciprocable into and out of effective position between the depresser and the corresponding punches, a magnet, an armature for said magnet, means for adjustably determining the position to be assumed by the armature when the magnet is energized and a connection between the armature and the depresser for actuating the latter and adjustable for independently of the aforesaid means determining the limit of the throw of the depresser and consequently of the punches.
12. In a record punching machine having a set of punches, a depresser overlying said punches and interposers reciprocable into and out of effective position between the depresser and the corresponding punches, a magnet, an armature for said magnet, means for adjustably determining the position to be assumed by the armature when the magnet is energized, a connection between the armature and the depresser for actuating the latter and adjustable for independently of the aforesaid means determining the limit of the throw of the depresser and consequently of the punches, and means independently of aforesaid means and said adjustable connection for determining the normal or retracted position

of the armature and consequently the clearance between the depresser and the interposers.

13. In a record punching machine having a set of punches, a depresser overlying said punches and interposers reciprocable into and out of effective position between the depresser and the corresponding punches, a magnet, an armature for said magnet, means for determining the position to be assumed by the armature when the magnet is energized, a connection between the armature and the depresser for actuating the latter and adjustable for determining the limit of the throw of the depresser and consequently of the punches, means for determining the normal or retracted position of the armature and consequently the clearance between the depresser and the interposers and adjusting means to position the magnet to provide clearance between the same and the armature when the magnet is energized.

14. In a record punching-machine having a set of punches, a punch-operating device and interposers movable between said device and said punches for operating the latter, a magnet, an armature therefor, and means, including an operating connection between said armature and said punch-operating device and eccentrically adjustable means for adjusting said connection, for determining the clearance between said device and said interposers.

15. In a record punching machine, a magnet, an armature therefor, a control circuit for said magnet punch-operating means connected with said armature for actuation by said magnet, a circuit making and breaking device for said circuit, and means adjustably secured to and actuated by the punch-operating means for actuating the circuit making and breaking device.

16. In a record punching machine, a set of punches, a depresser, interposers movable into position between said depresser and said punches for operating the punches, a magnet, an armature therefor, a controlling circuit for said magnet depresser-operating means actuatable by said armature, a contact device in said circuit, means operable by any one of said interposers for actuating said contact device, and an adjustable means actuatable by said magnet for restoring the magnet circuit to its initial status.

17. In a record punching machine, a set of punches, a depresser, interposers movable into effective position between said depresser and said punches, a magnet, an armature therefor, depresser-operating means actuatable by said armature, a normally open contact device in the magnet circuit comprising a fixed contact and a movable contact biased away from the fixed contact, a device actuatable by any of said interposers in moving to effective position, for engaging and moving the mov-

able contact into engagement with the fixed contact, a device actuatable by the armature independently of any of the interposers for disconnecting the contact moving device from the movable contact, and means for adjusting said disconnecting device to determine the instant of operation thereof.

18. In a record punching machine, a set of punches, a depresser, interposers movable into effective position between said depresser and said punches, a magnet, an armature therefor, depresser-operating means including a link pivoted to said armature and extending away from said magnet, a normally open contact device in the magnet circuit comprising a fixed contact and a movable contact biased away from the fixed contact, a link having a hook portion to engage and pull the movable contact into engagement with the fixed contact to close the magnet circuit, means operable by any one of said interposers for shifting the last mentioned link to close the contact device, and means for disconnecting the second mentioned link from the movable contact including a device adjustably mounted on the first mentioned link.

19. In a record punching machine, a punch operating device, a punch selecting device, a magnet, an armature therefor connected with said punch operating device by means including a reciprocable link, means including a link operable by the punch selecting device, for closing the circuit of said magnet, and means rendered effective by the movement of the armature toward the magnet for breaking the magnet circuit, said circuit breaking means including a member pivoted on the first mentioned link so as to engage the second mentioned link and shift the same to break the magnet circuit and means to adjustably secure said pivoted member on the first mentioned link in a position to effect circuit breaking at the proper time.

20. In a record punching machine, a punch operating device, a punch selecting device, a magnet, an armature therefor connected with said punch operating device by means including a reciprocable link, means including a link operable by the punch selecting device, for closing the circuit of said magnet, and means rendered effective by the movement of the armature toward the magnet for breaking the magnet circuit, said circuit breaking means including a member pivoted on the first mentioned link so as to engage the second mentioned link and shift the same to break the magnet circuit and means, including a set screw passing through a slot in said member concentric with the pivot thereof, to adjustably secure said pivoted member on the first mentioned link in a position to effect circuit breaking at the proper time.

21. In a record punching machine, a magnet, an armature therefor, punch-operating means actuatable by said armature, a stationary

device at the other side of the armature from the magnet for engaging the armature upon its movement away from the magnet for limiting the movement in one direction of
5 the punch-operating means, and means connected to the frame and to the armature for positively arresting the movement of the punch operating means in the direction opposite to aforesaid direction at a definite, pre-
10 determined point for preventing the shock of engagement of the armature and said magnet.

22. In a machine provided with punches, a magnet, an armature therefor, punch-operating means actuated by said armature, a stationary frame, and a device adjustably carried by said frame and including a link attached to said armature for positively stopping said armature at one end of its stroke in a definite, predetermined position, the adjustment of said device serving to predetermine said position and simultaneously serving to thereby adjust the stroke of the punch-operating means.

In testimony whereof I hereto affix my signature.
